UNITED STATES PATENT OFFICE.

BENJAMIN HURTUBES, OF RAHWAY, NEW JERSEY.

WINDOW-SASH.

SPECIFICATION forming part of Letters Patent No. 276,416, dated April 24, 1883.

Application filed December 19, 1881. (No model.)

To all whom it may concern:

Be it known that I, BENJAMIN HURTUBES, of Rahway, in the State of New Jersey, have invented certain new and useful Improvements in Noiseless Sashes for Carriage or Car Windows; and I do hereby declare that the following is a full description thereof, reference being had to the accompanying drawings, in which—

10 Figure 1 is a side elevation, showing a carriage-window sash with my stiffened rubber "buffer" applied. Fig. 2 is a horizontal cross-section of same. Fig. 3 is a side view, partly in section, through the buffer. Fig. 4 is an 15 edge view of Fig. 1. Fig. 5 is a horizontal cross-section through the buffer; Fig. 6, a similar section through the buffer and one of its retaining-screws.

One of the difficulties in making carriage- 20 window sashes is to avoid the noise, rattling, and jarring due to the contact between the edges of the sash and the edges of the grooves of the frame in which it plays.

My invention overcomes this difficulty; and 25 it consists in applying to each vertical edge of carriage or car window sashes a stiffened rubber buffer consisting of a flattened rubber tube of suitable cross-section closely surrounding a metallic bar or stiffener, so that 30 two screws, one near each end, passing through the rubber buffer and its metallic "stiffener," will firmly secure the same to the sash without impairing the elasticity and noise-preventing qualities of the buffer.

35 A shows a carriage-window sash; B, the frame in which it slides; C, the rubber buffer, which I prefer to have made of soft vulcanized rubber in the form of a flat hollow tube having a quadrilateral cross-section, as shown 40 in Figs. 2 and 5. Its width is equal to that of the edge of the sash, and its thickness is sufficient to give desired elasticity—ordinarily from one-fourth to three-fourths of an inch. In the center of this tube C is tightly inserted 45 the metallic stiffener D, of the same cross-section as the interior of tube C. The tubes C may be made in continuous tubes, and be cut to proper sash lengths by the sash-finisher; or they may be made of proper lengths for a 50 sash, and the rubber (soft vulcanized) placed

directly upon and around the stiffener, either in long strips or in sash lengths, with the rubber covering the stiffener at the ends as well as around the sides.

5 E are two screws securing my improved buffer to the sash. These screws pass clear through the rubber and are countersunk in the metal stiffener. By my construction the rubber buffer is stiffened without sacrifice of elasticity, and the screw-heads are kept from 60 contact with the sash-frame, thus securing for my invention a high degree of durability and freedom from noise, the sash being held firmly in its frame without jar or rattling.

I am aware that a window-sash frame provided with semi-cylindrical grooves in its vertical edges, adapted to receive one end of a strip of rubber held in the groove by a wooden strip inserted in it over the rubber, the wooden strip being held in the groove by screws, and 70 the free end of the rubber strip being folded over the front face of the wooden strip and lying in the recess between the front face of the wooden strip and the frame in which the sash slides, has heretofore been employed; but in this construction the free end of the rubber, not being secured, is liable to wrinkle and bind in the recess in the frame in which the sash slides and the device become inoperative; and I am also aware that a flexible tube having a metal rod 75 passing through it, and secured to a swinging door near its lower end, and acting as a weather-strip, has heretofore been employed; and I therefore lay no claim to such inventions.

I claim—

80 As an improved article of manufacture, the flat hollow tube C, quadrilateral in cross-section, and provided with the stiffener D, the tube and stiffener being secured together by screws and the whole adapted to be applied 85 to a window-sash, substantially as herein shown and described.

In testimony that I claim the above improvements in noiseless window-sashes I have hereunto set my hand this 15th day of November, A. D. 1880.

BENJAMIN HURTUBES.
